SECURING DEVICE

Gustave François Leon Gilbert, Houilles, France

Application January 22, 1938, Serial No. 186,311
In France January 25, 1937

5 Claims. (Cl. 85—9)

The present invention relates to an improved securing device.

It is known that for assembling two metal sheets of large dimensions by means of rivets it is necessary to secure them together in a detachable manner at several points before proceeding to drill the holes intended to receive the rivets, and then to drive in the said rivets.

The preliminary securing of the sheets to be assembled is generally effected by means of nuts and bolts. This method of securing can only be carried out in the case of large sheets by at least two persons, one being occupied with the fitting of the bolts and the other with the fitting of the nuts. In certain cases, in particular in aircraft construction, this method of securing is not only lengthy and complicated, but also very difficult to carry out.

The subject of the invention is an inexpensive securing device of easy manipulation, by means of which it is possible to connect temporarily employing only one hand, two or more metal sheets to be assembled by rivets.

The device according to the invention is essentially characterised in that it comprises in combination a clip-like member having two resilient branches and a rod slidably mounted with respect to the clip, the said rod being intended to move the two branches of the clip together or apart according to the position which it occupies with respect to the branches of the said clip.

In order that the invention may more readily be understood and carried into practice embodiments thereof will now be described, solely, by way of example, with reference to the accompanying drawing, in which:

Fig. 1 is an elevational view of the securing device in the position in which it detachably connects two sheets together.

Fig. 2 is a profile view corresponding to that of Fig. 1.

Fig. 3 is a vertical sectional view corresponding to that of Fig. 1.

Fig. 4 is a view similar to that shown in Fig. 3, showing the device in the position in which the two branches of the clip no longer connect the two sheets together, and

Fig. 5 is a sectional view on the line V—V of Fig. 3, showing the section of the two branches of the clip.

According to the constructional example illustrated, the securing device intended, as has been stated, for temporarily and detachably connecting two sheets, such as 1 and 2, is formed of a clip-like member designated generally by 3 in Figure 2,

and of a rod 4 slidably mounted with respect to the said clip.

The clip 3 comprises two branches 5 and 6 and a flat part 7, the latter being joined to the said branches by two curved parts 8 and 9 forming a spring. These curved parts 8 and 9 tend to move the two branches 5 and 6 together. In section, the two branches 5 and 6 are substantially semi-circular as may be seen from Figure 5. Furthermore, when the two branches 5 and 6 have been moved together (Fig. 4) they have at their upper part the form of a truncated cone extended by a constricted part 10 (Fig. 2) which in turn is extended by a lower part 11 also of truncated cone form.

It should be noted that the largest diameter of the truncated cone portion 11 must at the most be equal, when the two branches 5 and 6 have been brought together, to the diameter of the holes drilled in the sheets to be temporarily assembled.

The clip 3 is preferably formed by cutting and shaping from a metal blank.

The rod 4 has at one of its extremities a screw-threaded cylindrical part 12 and terminates at 25 its other extremity 13 in the form of a point. Between the two extremities of the rod 4 is provided a constricted portion 14.

The largest diameter of the point 13 is greater than the diameter of the cylindrical part 12, this 30 diameter being, however, at the most equal to that of the holes drilled in the sheets 1 and 2 to be assembled.

As is shown, the rod 14 traverses the part 7 of the clip 3 in a substantially axial direction.

The screw-threaded part 12 receives a nut 15, a spring 16 being provided about the rod 4 and being interposed between the lower face of the nut 15 and the upper face of the part 7 of the clip.

The tension of the spring 16 is such that in the position of rest the point 13 is disposed between the branches 5 and 6 at the level of the truncated cone 11. It should be noted that in this position the largest diameter of the said truncated cone portion is greater than the diameter of the holes drilled in the sheets 1 and 2 to be assembled.

The device described is utilised in the following manner:

When the two sheets 1 and 2 to be assembled have been drilled with a certain number of holes lying opposite one another, the rod 4 is shifted with respect to the clip 3 in order to place the device in position, so that the constricted part 14

of the said rod 4 comes level with the narrowed portion 10 of the two branches 5 and 6. In this position (Fig. 4) it is possible to engage the pointed extremity of the rod 4 and the extremity 5 of the two branches 5 and 6 of the clip 3 in the holes made in the sheets 1 and 2.

When the securing device has been introduced as above described into the holes in the sheets 1 and 2, it is sufficient to cease exerting pressure 10 on the rod 4 to enable it, under the action of the spring 16, to take up the position in which it is shown in Fig. 3. At this moment, the securing device can no longer be disengaged from the holes in the sheets 1 and 2. In order to increase 15 the pressure exerted by the branches 5 and 6 of the clip in the said holes it is sufficient to compress the spring 16 by screwing the nut 15.

In order to remove the securing device, the 20 above described operations are repeated in the opposite sequence.

Although the securing device described is more particularly intended for the temporary connection of two sheets to be assembled by rivets, it is obvious that this securing device may also be 25 utilised for holding in position any members requiring to be detachably secured. Thus, for example, the device could be utilised as a cap-attaching device.

The rod 4, moving the branches 5 and 6 of the 30 clip 3 apart could, instead of acting by tractive force as indicated, also act by thrust. In the same way, the rod 4, instead of causing the branches 5 and 6 of the clip 3 to move apart in the position of rest, could act in the inverse 35 sense.

It is obvious that the invention is in nowise limited to the embodiments which have been more especially described by way of example, but

that it extends to all possible modifications coming, fairly, within the scope of the appended claims.

I claim:

1. In a device to secure plates together a resilient member formed by a clip having two branches, a rod slidably mounted with respect to the said clip, said rod being provided with means enabling to move apart said branches according to the position which it occupies with respect to the branches of the said clip. 5

2. In a device to secure plates together a resilient member formed by a clip having two branches of semi-circular section joined to a flat part by two curved parts forming a spring, a rod 15 slidably mounted with respect to the said clip, said rod being provided with means enabling to move apart said branches according to the position which it occupies with respect to the branches of the said clip.

3. In a securing device according to claim 2, said branches having in longitudinal section the form of two parts of truncated cone shape connected by a constricted part, said plates received in said constricted part. 25

4. In a device to secure plates together a resilient clip formed by two branches of semi-circular section joined to a flat part by two curved parts forming a spring, a rod traversing said flat part and slidably mounted with respect to the 30 said clip, and a spring interposed between the upper face of said flat part and a member carried by said rod.

5. In a securing device according to claim 4 said rod comprising a screw threaded cylindrical 35 extremity connected by a constricted part to a part in the form of a point.

GUSTAVE FRANCOIS LEON GILBERT.
